Primary Examiner — David G Muller

CLAIM

I claim the ornamental design for an injection instrument, as shown and described.

DESCRIPTION

FIG. 1 is a perspective view of an injection instrument showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of parts of the drawings is included for the purpose of illustrating use and environment and forms no part of the claimed design.

1 Claim, 7 Drawing Sheets
